(57) **CLAIM**

The ornamental design for measuring spoon set, as shown and described.

DESCRIPTION

FIG. 1 is a perspective view of a measuring spoon set according to the present invention.

FIG. 2 is a perspective view of the measuring spoon set shown in FIG. 1, with the spoons spread apart and one spoon detached.

FIG. 3 is a front view of the measuring spoon set shown in FIGS. 1 and 2.

FIG. 4 is a rear view of the measuring spoon set shown in FIGS. 1-3.

FIG. 5 is a side view of the measuring spoon set shown in FIGS. 1-4.

FIG. 6 is a bottom end view of the measuring spoon set shown in FIGS. 1-5.

FIG. 7 is a top end view of the measuring spoon set shown in FIG. 6; and,

FIG. 8 is an exploded bottom end view of the detachable spoons included in the measuring spoon set shown in FIGS. 1-7.
